CLAIM

The ornamental design for decorative glass, as shown and described.

DESCRIPTION

FIG. 1 is an isometric view of a decorative glass showing the upper and lower edges of the decorative band in solid lines and the portions between the upper and lower edges of the decorative band shown in phantom. The phantom lines form no part of the claimed design;

FIG. 2 is a front elevational view of FIG. 1;

FIG. 3 is a top plan view of FIG. 1; and,

FIG. 4 is a bottom plan view of FIG. 1.
